UNITED STATES PATENT OFFICE.

ALFRED E. ANDERSON AND HARRY FELDEEN, OF ROCKFORD, ILLINOIS.

DAVENPORT OR CHAIR.

1,295,411.

Specification of Letters Patent. Patented Feb. 25, 1919.

Application filed July 6, 1918. Serial No. 243,642.

To all whom it may concern:

Be it known that we, ALFRED E. ANDERSON and HARRY FELDEEN, citizens of the United States, and residents of Rockford, in the county of Winnebago and State of Illinois, have invented certain new and useful Improvements in Davenports or Chairs, of which the following is a specification.

Our invention relates to improvements in davenports or chairs, and particularly to the construction of davenport or chair ends, our object being the provision of an end construction which will enable wide range in thickness to suit davenports or chairs of light, heavy, and medium construction, which will be applicable to davenports, chairs, rockers, or straight chairs, which will obviate loosening and rattling of parts and which will present great strength and durability and avoid warping and disalignment.

In our present construction the davenport or chair end results in substantially a one-piece construction, although it is built up of several plies, thus giving in the manufacture maximum chance and opportunity to vary its strength as well as its ornamentation. The invention is thus applicable to expensive davenports or chairs of heavy construction as well as cheap davenports or chairs of light construction, and in each instance permits of greatly strengthening the davenport or chair as a whole.

In the accompanying drawings illustrating our present invention

Figure 1 is a perspective view of a davenport or chair constructed in accordance with our invention, and

Figs. 2 and 3 are respectively a vertical and a horizontal section taken on line 2--2 and 3--3 of Fig. 1.

Referring now to these figures, our invention contemplates a davenport or chair end construction in which the rear portion is supported by a depending integral extension 10 as seen in Fig. 1 which takes the place of the rear upright or supporting leg of the ordinary construction which we dispense with. The end 11 of the davenport or chair is when complete substantially a one-piece construction, uniting at its front side with the front style 12 and at its top with a top arm 13, the end 11 being similarly joined to the said style and top arm as will be presently described.

The end 11 consists of a core or central

plate 14 as clearly seen in Figs. 2 and 3 which is preferably in a single piece and receives at its opposite sides cross bands 15 and 16 securely fastened thereto and in turn receiving the veneering 17 and 18. It will be noted that along the upper and front sides of the davenport or chair end 11 the upper end of which may be suitably curved to conform to the curvature of the top arm 13, the core or central plate 14 is extended beyond the adjacent edges of the cross banding and veneering in order to form tongues which are securely held within conformable grooves 19 and 20 of the top arm 13 and front style 12 as also seen in Figs. 2 and 3, the shoulders formed by the adjacent edges of the cross banding and veneering along the inner portions of the tongues 21 and 22 being beveled so as to form longitudinal grooves along the inner faces of the top arm and front style to receive a surplusage of glue whereby a stronger union between the parts will result.

It is thus obvious that a davenport or chair end constructed in accordance with our invention avoids all parts likely to become loose and rattle as well as all warping and disalignment and we have found that a davenport or chair end so constructed will stand considerably more hard usage and strain than a solid board or the ordinary many-piece end.

It is also obvious that the thickness of the end, and thus the weight of the davenport or chair may be varied at will and that the invention is equally applicable to cheap and expensive davenport, chair, rocker or straight chair ends.

We claim:

1. An article of the character described having a several ply end provided at its rear lower portion with a depending extension, a front style and a top arm joined to the front and upper edges respectively of the end, the said several ply end having tongues along its front and upper edges entering into conformable grooves in the front style and top arm, the latter of which are beveled at opposite sides of their grooves to form glue receiving channels.

2. An article of the character described having an end comprising a single piece core member, cross banding joined to the opposite sides of the core member, and veneering secured to the cross banding, said core member being extended beyond the front and

upper edges of the said cross banding and veneering to form tongues along the front and upper edges of the end, and a front style and top arm having grooves to receive the said tongues as described.

3. An article of the character described having an end comprising a single piece core member, cross banding joined to the opposite sides of the core member, and veneering secured to the cross banding, said core member being extended beyond the front and upper edges of the said cross banding and veneering to form tongues along the front and upper edges of the end, and a front

style and top arm having grooves to receive 15 the said tongues as described, said front and upper edges of the cross banding and veneering along the inner portions of the tongues being beveled to form glue receiving channels between the same and the adjacent faces 20 of the front style and top arm when the tongues are extended into the said grooves.

ALFRED E. ANDERSON.
HARRY FELDEEN.
